(57) **CLAIM**

The ornamental design for a light fixture, as shown and described.

DESCRIPTION

FIG. 1 is a side elevation view of a light fixture in accordance with my design, all side views being identical;

FIG. 2 is a top plan view of the light fixture in accordance with my design taken along the lines 2—2 of FIG. 1; and,

FIG. 3 is a bottom plan view of the light fixture in accordance with my design.

The broken-line disclosure of elements is understood to represent portions of the article in which the design is embodied, but which form no part of the claimed design.

1 Claim, 3 Drawing Sheets
